VENTED LIQUID DISPENSING UNIT

Richard W. Beall, Jr., Hermosa Beach, Calif.

Application January 19, 1956, Serial No. 39,843

Term of patent 14 years

(Cl. D62—2)

FIG. 1.

FIG. 3.

FIG. 2.

FIG. 5.

FIG. 4.

FIG. 6.

Figure 1 is a perspective view of a vented liquid dispensing unit embodying my new design;

Figure 2 is a side elevational view thereof;

Figure 3 is a top plan view thereof;

Figure 4 is a bottom plan view thereof;

Figure 5 is a vertical section taken substantially on line 5—5 of Figure 1; and

Figure 6 is a vertical section taken on line 6—6 of Figure 1.

I claim:

The ornamental design for a vented liquid dispensing unit, substantially as shown.
